OF NEW YORK, N. Y.

DRIPLESS POURING-BOTTLE SEAL.

1,027,544.

Specification of Letters Patent.

Patented May 28, 1912.

Application filed August 17, 1911. Serial No. 644,694.

To all whom it may concern:

Be it known that I, CLARENCE S. JACKSON, a citizen of the United States, residing in New York city, in the county of New York and State of New York, have invented certain new and useful Improvements in Dripless Pouring-Bottle Seals, of which the following is a specification.

My present invention relates to an improvement in bottle closures of the type that control the volume of flow of the contained fluid, said control of the volume being variable at will.

One of the advantages of my device is that due to the peculiar arrangement of the contacting faces of the closure member, I am enabled to regulate the opening from a full flow down to a complete sealing of said stopper. The stopper may also be regulated so that it may be used as a dropper, the number of drops per minute being absolutely controllable.

The most important feature of my invention, however, lies in the manner in which the flow through the stopper is controlled so that it is positively dripless. In other words, when through pouring, the bottle may be set upright and not a drop of fluid can escape to run down the sides of the bottle, but is sucked backward and inward to finally flow into the main contents. This important feature is due entirely to the peculiar manner in which the pouring passage is constricted, thereby causing the law of capillarity to control the fluid contained within the stopper passage proper immediately after the pressure of the contents is removed or the bottle replaced in an upright position.

A further advantage is the simplicity of the stopper, it being comprised of only four parts and its consequent cheapness of manufacture makes it more desirable.

A further improvement consists of coating the seal with a glossy finishing material, preferably waterproof, thereby enhancing the creeping or capillary action of the fluids, especially in the pouring passage.

In the drawings, Figure 1 shows the seal in section, and as taken on line 1—1, Fig. 2. Fig. 2 is a bottom view of Fig. 4. Fig. 3 is a sectional view of another modification, in section. Fig. 4 is a sectional view of another modification of Fig. 1.

In Fig. 1 the closure member 1 is shown

as having embedded therein a threaded shank member 2, the threaded portion being screwed into a bushing or body member 3, with a sealing disk 4 between the opposing surfaces, forming the passage 5. While the closure member 1 may be made of any suitable material I prefer to make it and its bushing member 3 of bass-wood as this wood has advantages over cork, and also has distinguishing features of its own as a sealing material. Its compressibility is not so great as cork but is enough for all practical purposes and when the portion 6 is forced into a bottle neck 7, a part of which is shown in section in Fig. 1, I find it is very difficult to remove the seal without badly marring the same. The most important feature of my device, however, is the manner in which, as before stated, I prevent dripping of the fluid after pouring, which, if not prevented, not only mars the appearance of the bottle but also may cause soiling of the hands, which is usually very disagreeable, especially in the case of ink or other staining fluids which are difficult to remove.

The manner in which the stopper prevents drip is accomplished by so constricting the pouring passage 5 that when the fluid passes through the apertures 8 it enters the central portion of the passage 5 which is of less width than the outer annular mouth 9, and upon being set in upright position the said constricted portion 10 and the downward or bowl-shaped formation of said passage cause the fluid remaining in said passageway to flow back toward the apertures 8 and this double force of capillarity and gravity sucks back any of the fluid remaining in said passage or overhanging the edge 11, and is then returned to the bottle interior.

A further improvement in making the stopper absolutely dripless is the formation of the thin edges 11 and 12 formed by the two lips on the bushing 3 and the closure members 1, respectively. This thin edge tends to cut the stream cleanly and short when the bottle is being returned to the vertical after pouring and these edges afford little or no surfaces for a drop to cling to and due to the phenomena of capillarity previously mentioned, the drop is forced to retreat within the confines of the lips 11 and 12 and from thence to flow back into the bottle proper.

The difference, previously noted, of verti-

cal width in the passageway 5 may be obtained by two different methods, one of which, as indicated in Fig. 1, is caused by the sealing face 12' of the closure member 1 being spherical with a radius equal to A and the depressed or seat portion 13 being of a somewhat larger radius, as B. This construction, it will be noted, causes a constriction at the central portion of the passage 5, as at 10, and leaves a wide flaring mouth around the periphery, as indicated at 9, so that when the seal is drawn down tight upon the bushing member 3 and has compressed the sealing disk 4, the pouring mouth, as at 9, is still slightly open.

Another form of obtaining the bowl shape passage 5 with a constricted point in said passage, is by forming the closure member 1 similar to that indicated in Fig. 1 with the bushing member 3 having a cone shaped seat instead of a spherical one, as indicated in Fig. 3. The angle C being just enough to cause the fluid to flow back into the apertures 8 and it is obvious that a construction of the pouring passage occurs at a point 10' of the spherical seat 12'.

In Fig. 4 the members 1 and 3 in their general construction are similar to that indicated in Fig. 3, with the exception of the screw member 14 which is reversed and embedded in the bushing member 3, thus permitting the closure member 1 to ride up and down upon the opposite end of the said screw, whereas in the construction shown in Fig. 1 the operation is exactly reversed.

As a further aid to capillary action of the fluid, the seal is coated with a glossy coat of preferably fluid-proof material, such as Japan, this glossy coating causing the fluid to creep, thus aiding in capillary condensing the fluid contained in the bowl-like passage 5.

I am aware that bottle seals have been made with apertures therein and with an adjustable stopper for closing said apertures, but none of these stoppers have made

provision or have structure that will prevent drip after pouring. I have practically proved by tests that it is impossible to obtain a drip from this pouring seal and this important advantage is due entirely to the arrangement of the bowl shaped passage having its constricted portion near the apertures of the bushing and coating the parts with a glossy material which aids in amplifying the capillary action of the fluids between the two contiguous surfaces. The sealing disk 4, previously noted, is preferably composed of a porous, fibrous, material, such as paper saturated with paraffin or other satisfactory compound, and the disk being slightly compressible, effects to seal the apertures 8 when the closure member 1 is screwed down upon its seat. Instead of permitting the disk 4 to be loose between the two members 1 and 3, I prefer to have it fixed on the under seat portion 12' of the member 1.

Having thus described my invention, I claim:

A dripless pouring bottle seal comprised of an apertured flared bushing and an adjustable stopper, an annular fluid passageway therebetween, said passageway being formed by the contiguous adjustable surfaces between said bushing and said stopper and being depressed at its central portion and leading upwardly and terminating in an annular double lipped pouring mouth, the said lips being substantially in the same vertical plane, the vertical width of said passageway being constricted at its central interior and terminating at a greater width at its outer diameter for the purpose of causing a capillary and gravitational withdrawal of fluid from the outer diameter of said passageway when the pressure of the contents of the bottle is removed.

CLARENCE S. JACKSON.
